UNITED STATES PATENT OFFICE.

JAMES BUCHANAN, OF WEST ALBANY, NEW YORK.

LOCOMOTIVE OR ENGINE CYLINDER BORING MECHANISM.

SPECIFICATION forming part of Letters Patent No. 531,773, dated January 1, 1895.

Application filed June 1, 1894. Serial No. 513,118. (No model.)

To all whom it may concern:

Be it known that I, JAMES BUCHANAN, a citizen of the United States, residing at West Albany, in the county of Albany and State of New York, have invented a certain new and useful Locomotive or Engine Cylinder Boring Mechanism, of which the following is a specification.

Heretofore it has been customary, so far as

- 10 I am aware, when the cylinder of a locomotive became worn or enlarged to bore it out when in place on the locomotive by means of mechanism operated by hand, so that the piston would work properly therein. This method
- 15 of operating the boring mechanism by hand, &c., was exceedingly costly, as well as consuming a large amount of time and thus keeping the locomotive out of service longer than desirable
- 20 The object of my invention, therefore, is to provide means whereby the cylinders of a locomotive can be bored out or trued when in place on the locomotive by the application of power, &c., by which means a large amount of
- 25 time and inconvenience can be saved.

Another object of my invention is to provide devices for facing off the valve seat of the valve chest, which devices are operated in conjunction with the above mentioned boring devices.

Another object of my invention is to provide improvements in an oscillating engine to be used in operating my cylinder boring devices.

35 A further object of the invention is to provide means for giving an intermittent feeding motion to the boring or cutting tool used for truing the cylinder.

My invention, therefore, consists in a boring mechanism adapted to be fitted upon, or applied to, a locomotive or engine cylinder in such manner that the interior of said cylinder can be evenly and properly bored while it remains in position on the locomotive.

40 The invention also consists in the application to such a mechanism of an independent engine adapted to operate said mechanism and to be driven by steam or compressed air from said locomotive or other means carried thereby.

The invention also consists in means for giving the boring tool a continuous rotary

motion with an intermittent feed so as to produce the most perfect boring within the cylinder. This feature is in contradistinction to 55 the usual practice of advancing the tool continuously during its revolutions.

The invention also consists in means for facing the valve seat for connecting said means with the boring devices so that they may operate them simultaneously by the same power.

The invention also consists in novel means for attaching the boring devices and their engine to the cylinder and locomotive so as to produce perfect action in the parts while permitting of quick and ready adjustment.

The invention further consists in the novel details of improvement and the combinations of parts that will be more fully hereinafter set forth and then pointed out in the claims.

Reference is to be had to the accompanying drawings, forming part hereof, wherein—

Figure 1 is a partly broken side elevation of a locomotive showing my improvements in position on the cylinder for boring or truing 75 it. Fig. 1^a is a detail hereinafter explained. Fig. 2 is an enlarged side view of the cylinder and the attached boring devices. Fig. 3 is a side view of the engine cylinder for operating the boring devices. Fig. 4 is a longitudinal section thereof. Fig. 5 is an enlarged plan view of the locomotive cylinder and the attached boring devices. Fig. 6 is a side elevation of the engine for operating the boring devices. Fig. 7 is a view looking from 85 the opposite side thereof. Fig. 8 is an end view thereof, showing means for attaching said engine to the locomotive cylinder. Fig. 9 is a partly sectional detail view showing means for giving the boring tool an intermittent feeding motion. Fig. 10 is a cross section thereof looking in the direction of the arrow x', and Fig. 11 is a similar section looking in the direction of the arrow z' in Fig. 9. Fig. 12 is a detail view showing means for 95 regulating the feeding motion of the cutting or boring tool. Fig. 13 is a partly broken plan view of the devices for facing off the valve seat in the valve chest. Fig. 14 is a partly sectional side view thereof, and Figs. 15 and 16 are detail side views of the latter devices showing the direct application of the engine thereto.

In the accompanying drawings, in which

similar numerals of reference indicate corresponding parts in the several views, the numeral 1 indicates a portion of a locomotive and 2 is one of its cylinders shown in position thereon. In the example shown the heads of the cylinder are removed and a boring shaft or spindle 3 is shown passing centrally through said cylinder. The shaft or spindle 3 is shown provided with a tool carrier 4 having a suitable tool 5, that is adapted to engage and cut the inner wall 6 of the cylinder. (See Fig. 1.) Two tools 5 are shown on the carrier 4, but three or more may be used, and the carrier 4 and tools 5 may be suitably arranged to cut and true the interior of the cylinder. The shaft or spindle 3 is shown journaled in bearings 7 shown carried by suitable brackets or yokes 8, that are secured on the ends of the cylinder 2. The brackets or yokes 8 are, or may be, secured on the ends of the cylinder 2 by screws or bolts 9 that may enter the holes that receive the screws for holding the cylinder heads in position. By this means the shaft or spindle 3 may be readily centered on the cylinder while the latter is in position on the locomotive and without necessitating its removal therefrom.

The shaft or spindle 3 is to be given a rotary, as well as longitudinal feeding, motion for the purpose of causing the cutter or tool to operate on the interior of the cylinder, and for this purpose I have shown an engine 10, as adapted to be connected with the cylinder 2 and to actuate said shaft or spindle. The engine 10, while it may be of any desired construction, is shown of the oscillating type, having a cylinder 10^a, mounted on trunnions 11, carried by a suitable frame arranged to be supported by the cylinder 2. The said frame is made adjustable so that it may be applied to cylinders of different dimensions. Said frame is shown constructed as follows: 12 is a yoke-like portion at the end of one arm in which a trunnion 11 of the cylinder 10^a is journaled, the opposite member of said yoke having bolted to it the face plate 13 of the cylinder 10^a. The plate 13 carries a projecting web or arm 14, shown extending at right angles so as to bear against the end of the cylinder 2, whereby it is supported. The web or arm 14 is shown in Fig. 8 as provided with a curved slot 15 that is adapted to receive bolts or screws 16 that enter holes in the end of the cylinder 2, whereby said web 15 or arm may be adjustably attached to said cylinder. By this means one end of the yoke 12 is conveniently attached to said cylinder, and it may be adjusted into the desired positions to bring the parts in proper positions on the cylinder. The trunnion 11^a of the cylinder 10^a is shown journaled in the plate 13, and provided with a tension spring 17 to hold the ports of the cylinder against the plate 13 in well known manner. The cross bar 12^a of the yoke 12 is shown connected with the bent end 18^a of a bar 18 by a bolt 18^b, the bar 18 having a slot 19 to receive a bolt 19^a that

passes into a similar slot 20^a in a bar 20. The bar 20 has a bent end 20^b that fits against the end of the cylinder 2 by a bolt 20^c. By the foregoing construction the parts 14 and 20 can be secured to the respective ends of the cylinder 2, and the difference in lengths of different cylinders can be compensated for by means of the slots 19 and 20^a and bolt 19^a. The yoke 12 is shown provided with bearings 21 in which is journaled a crank shaft 22 carrying pulleys 23, 24 at opposite ends. The piston rod 31 of the cylinder 10^a connects with the crank 22^a of shaft 22, whereby said shaft is turned.

The cylinder 10^a may be supplied with steam or compressed air from the locomotive 1, or from any other source, through a pipe 25, which may be provided with a suitable cock 26. For example, the air pipe 25^a, having the flexible connection 25^b, and coupling 25^c, can be connected to the valve 26 by the flexible section 26^a, and thus supply the engine with compressed air. The steam supply pipe can likewise be connected; or an air or steam supply taken from any convenient source. To conveniently supply the cylinder 10^a with steam or air, and to permit the exhaust to take place I have shown the following arrangement: The plate 13 has exhaust holes 13^a, 13^b that are adapted to alternately align with ports 13^c, 13^d in the cylinder 10^a (see Figs. 3, 4 and 6) as the cylinder oscillates. The ports 13^c and 13^d are also adapted to alternately align with ports 26, 27 in a bar 28 having a steam or air channel 29, the channel 29 communicating with the pipe 25, as in Fig. 6. The bar 28 is secured to the plate 13, and it is bent at 30 to permit the passage of the trunnion or pivot 11^a. With this arrangement as the cylinder 10^a oscillates its ports 13^c, 13^d will alternately align with ports 26, 27 to receive steam and with holes 13^b, 13^a to permit the exhaust to take place. 31 is the piston rod of cylinder 10^a that connects with the crank on shaft 22; but it will be understood that any other desired arrangement of engine or means for operating the drive shaft 22 may be used.

The shaft 22 is designed to communicate rotary motion to the boring shaft or spindle 3, and for this purpose I have provided the following arrangement: At 32 is a frame or yoke shown supported at one end 33 by a standard 34, which may be secured on a tie, beam or flooring 35. (See Fig. 1.) The standard or support 34 is shown connected with the frame or yoke 32 by a bolt 36. The standard 34 is made vertically adjustable to regulate the height of the frame or yoke 32 relatively to the shaft or spindle 3, and for this purpose said standard is shown made in two parts 34^a, 34^b, the part 34^a consisting of a yoke having a horizontal part 34^c that receives the part 34^b, locking nuts 34^d being used to hold the parts 34^a and 34^b together and also permit of their adjustment.

At the end 33^a of frame or yoke 32 is jour-

naled the hub 36^a of a gear wheel 37, the shaft or spindle 3 passing through said hub as shown. The shaft 3 is keyed to the hub 36^a by a spline and feather 37^a, 38, or otherwise, 5 so that said shaft or spindle 3 will be turned by the hub 36^a, and yet have longitudinal movement therein. The gear wheel 37 meshes with a pinion 39 carried by a shaft 40 journaled on the frame 32, a spur wheel 41 on said 10 shaft also meshing with a pinion 42 on a shaft 43 journaled in the frame or yoke 32. The shaft 43 carries a bevel gear 44 that meshes with a similar gear 45 on a shaft 46 journaled on the frame 32. The shaft 46 also carries a 15 pulley 47 that receives a belt 48 from the pulley 23, whereby the shaft 46 is turned. By the above arrangement of gearing the shaft 22 causes the shaft or spindle 3 to rotate, and at the desired speed according to the relation 20 of the gearing; but it will be understood that any other suitable arrangement of device may be provided for turning the shaft or spindle 3 from the shaft 22, so long as the feature of adjustably attaching the spindle 3 and 25 an engine to the cylinder of a locomotive or engine is carried out.

The spindle or shaft 3 while rotating should be given a longitudinal feeding motion to advance the tool 5 to the work. I prefer to give 30 the shaft 3 an intermittent longitudinal feeding motion, rather than a continuous feeding motion, and for this purpose I have provided the following arrangement, which is clearly shown in Figs. 1, 9, 10, 11 and 12: One end of 35 the shaft or spindle 3 is shown provided with a longitudinal bore 3^a, which receives a screw 50, stationarily supported in any desired manner. For the purpose of conveniently attaching the screw 50 to the locomotive, in line with 40 the axis of the cylinder 2, I connect said screw with a plate 51 that is clamped on the guide yoke or slotted plate 52 that receives the connecting rod of the locomotive. The plate 51 receives bolts 51^a that pass into a corresponding plate 51^b on the other side of the yoke, 45 whereby the plates 51 and 51^b may be adjustably held on the part 52.

53 is an internally threaded sleeve that travels on the screw 50, and it is provided 50 with a spur wheel 54 whereby it may be turned to advance it along said screw. The shaft or spindle 3 carries a pawl 55 that is adapted to engage the wheel 54 to turn the sleeve 53 and thus advance it along the screw 50 to move 55 the shaft 3 longitudinally. The pawl 55 is shown carried by a spindle 56 journaled on a projection 57 carried on the shaft or spindle 3. The spindle 56 also carries a toe 58 that is acted upon by a spring 59 carried by the 60 shaft 3 or its projection 57, whereby the pawl 55 is kept in engagement with the wheel 54. To cause the sleeve 53 to be turned intermittently, to advance the shaft or spindle step by step, I permit the pawl 55 to be in engagement 65 with the wheel 54 for a portion only of each turn of the shaft or spindle 3; or in other words the pawl 55 is lifted from the wheel 54

after the latter has been turned the desired distance during each revolution. For this purpose I provide a notched disk 60, upon 70 which the pawl 55 can ride, and which is preferably located between the end of the shaft 3 and sleeve 53, the screw 50 also passing freely through said disk; but the disk does not turn on said screw, being held from turning by a spline cut in the screw 50, and feather 75 61, 62, as shown in Fig. 9. The disk 60 is of about the diameter of the wheel 54, so that when the pawl 55 bears on said disk it will be held out of engagement with the teeth of the 80 wheel 54. At this time the shaft or spindle 3 can turn without being advanced, but when the pawl 55 reaches the notch 63 in the disk 60 it will encounter a tooth of the wheel 54 and thus turn said wheel and sleeve 53 to 85 cause said sleeve, by being thus turned, to advance along the screw 50 to move the shaft 3 longitudinally a short distance. When the pawl 55 reaches the edge 64 of the notch 63 in the disk 60, it will ride up thereon and then 90 bear upon the periphery of said disk, being thus disengaged from the wheel 54, which comes to rest while the spindle 3 continues to turn. Thus an intermittent or step by step longitudinal movement is given to the sleeve 95 53 along the screw 50, the sleeve 53 moving the shaft or spindle 3 correspondingly, while it turns, to feed the tool 5 to the work within the cylinder.

In order to regulate the amount of longitudinal movement given the spindle 3 at each revolution I cause the pawl 55 to engage the teeth of the wheel 54 sooner or later, with relation to the edge 64 of the disk 60. This can be accomplished by means of an adjustable plate 65 having its outer edge curved to follow the periphery of the disk 60, as in Figs. 10 and 12. This plate is shown provided with a slot 66, through which passes a screw 67 that screws into the disk 60, a washer 68 acting to 105 assist in holding the parts together in the proper positions. The pawl 55 is adapted to slide off from the end 69 of the plate 65, so as to engage the teeth of the wheel 54, and thus according to the distance between the points 110 64 and 69 the pawl 55 will give the wheel 54 more or less rotary motion. Therefore when it is desired to advance the tool 5 more, the space between 64 and 69 is widened, and vice versa; but it is evident that the means for 115 moving the spindle 3 longitudinally may be varied, if desired.

By means of my invention I am also enabled to face off the valve seat of the valve chest or box on the cylinder 2 simultaneously 120 with the truing of the cylinder, and I also utilize the same engine 10 to operate both sets of cutting tools. For this purpose I have shown a cutting or planing mechanism, the specific structure, however, not being my invention, I do not claim herein, as follows: 70 is the valve seat of the cylinder 2 outside of which, preferably at the corners of a rectangle, are placed posts, standards or bolts 71,

which may be screwed into the desired holes 72 in the cylinder, by which the usual valve chest or box is held. (Not shown.) At 73 is a cutter supporting plate which is carried by 5 the posts or standards 71 above the valve seat 70. The plate 73 is adjustably connected with the posts 71 by arms 74, bolts or screws 75, 76 connecting said plate with said arms, while nuts, bolts or screws 77 connect said 10 arms with the posts or standards 71. (See Fig. 5.) In order to properly adjust the plate 73 over the valve seat 70 the arms 74 are provided with two concentric curved slots 78, 79 to receive the bolts or screws 76. Each arm 15 74 also has a longitudinal slot 80 to receive the bolt or screw 75, as well as two parallel longitudinal slots 81, 82 to receive the post 71 or screw or bolt 77. By this arrangement of slotted arms 74 and bolts or screws 71, 75, 76 20 and 77, the plate 73 can be adjusted in the desired position over the valve seat 70, and by this means provision is made for supporting the plate 73 over different sized valve seats, without requiring a plate for each sized 25 valve seat.

The plate 73 carries a central pivot 83 on which is hung or guided a rotative plate 84 which carries a cutting tool 85. (See Fig. 14.) The plate 84 is shown provided with a beveled periphery 84^a that bears against a correspondingly shaped ring 86 carried by the plate 73. The plate 84 has an internal gear 87 that meshes with a pinion 88 carried on a spindle 89, journaled in the plate 73, whereby 35 as said pinion turns the plate 84 will be carried around.

The spindle 89 may be driven direct, or by a gear wheel 90 secured to it and meshing with a pinion 91 on a spindle 92 journaled on 40 the plate 73. By this means the spindle 89 may be driven at different speeds by a constant source of power according to whether the spindle 89 is driven direct or by the spindle 92.

45 For the purpose of driving the spindle 89 by the same devices that drive the shaft or spindle 3 a shaft 93 is journaled in bearings 94 carried by the plate 73. The shaft 93 carries sleeves 95, 96, provided with bevel gears 97, 98, that may mesh with similar gears 99, 100 on the spindles 89, 92 respectively. The sleeves 95, 96 may be moved along the shaft 93 to cause the gears 97, 99, or 98, 100 to mesh respectively, according to the speed of rotation desired in the spindles 89, 92. The shaft 93 is shown provided with a pulley 101 that receives a belt 102 leading from the pulley 24 on the shaft 22. By this means as the shaft 22 is turned to operate the spindle 3 50 and tool 5 the shaft 93 will be turned to actuate the tool 85.

The adjustability of the frame supporting the engine and its associated mechanism in a line varying to and from the vertical enables the pulleys 23, 101 to be readily aligned 65 to freely drive the valve seat planer when

desired and also bring the pulley 47 into alignment.

The cutter or tool 85 is shown carried by a slide 103 that is actuated by a screw 104, carried in bearings 105 on the plate 84. The slide 103 is guided in suitable bearings 106 on the plate 84, so that it can be moved radially of said plate by said screw. The screw 104 is given an intermittent rotary motion as the 75 plate 84 turns, and for this purpose said screw carries a star wheel 107 that is adapted to engage a lug or projection 108 on the plate 73 as the plate 84 turns.

In planing or smoothing the valve seat 70 with this device the tool is moved toward the spindle 83, and as the plate 84 turns the star wheel 107 and lug 108 will cause the screw 104 to turn intermittently, whereby the tool or cutter 85 will be moved gradually across the 85 valve seat as well as being carried around it, whereby said valve seat will be smoothed or planed off.

From the foregoing description it will be observed that the devices for boring the cylinder and for facing off the valve seat are attachable to the respective parts of the cylinder, while said devices are operated simultaneously by the same motive power.

In Figs. 15 and 16 the shaft 93 is shown as 95 driven direct by the cylinder 10^a, in which case the piston rod 31 connects with a wrist pin 110 on the wheel 101, and said cylinder 10^a is carried direct by the cylinder 2, through the medium of the plate 14, adjustably secured to the bolt holes of the steam chest, as before described on the cylinder.

It is evident that the details of construction of the several parts, and the mode of operation may be changed and altered in some 105 particulars without departing from the spirit of my invention.

Having now described my invention, what I claim is—

1. A mechanism for boring a cylinder while 110 in position on a locomotive, comprising a shaft or spindle adapted to carry a tool or cutter, means for attaching said spindle to the cylinder, an engine or motor for rotating said shaft or spindle, means for supplying 115 said engine with steam or air from the locomotive to which it is attached, and means for moving said shaft or spindle longitudinally, substantially as described.

2. A mechanism for boring locomotive cylinders, comprising a shaft or spindle adapted to carry a tool or cutter, means for centrally supporting said shaft in said cylinder, an engine or motor for turning said shaft, means for attaching said engine or motor to said 125 cylinder, and means for operating said engine by steam or air obtained from the locomotive, substantially as described.

3. The combination of an adjustable frame 130 adapted to be attached to a locomotive cylinder, with an engine carried by said frame, and a cylinder boring device and means con-

necting said engine with said boring device to be operated by said engine and means for operating said engine by steam or air obtained from the locomotive, substantially as 5 described.

4. The combination of a shaft or spindle adapted to carry a tool or cutter within a locomotive cylinder, bridges or yokes adapted to be attached to the ends of said cylinder, and bearings for said shaft carried by said bridges or yokes, with an engine adapted to be attached to said cylinder, and devices connecting said engine with said shaft, and means for operating said engine by steam or air obtained from the locomotive, as and for the purposes specified.

5. The combination of a shaft or spindle adapted to carry a tool or cutter within a locomotive cylinder, bearings for said shaft 10 adapted to be attached to the ends of said cylinder, a frame adapted to be attached to said cylinder, and an engine carried by said frame, with a frame adapted to be journaled on said shaft, and mechanism carried by said frame and connected with said engine and means for operating said engine by steam or air obtained from the locomotive, for transmitting motion to said shaft, substantially as 15 described.

6. The combination of a shaft or spindle 3 adapted to carry a tool or cutter, a frame adapted to be connected with a locomotive cylinder, and an engine carried by said frame, with a frame having mechanism for transmitting motion from said engine to said shaft, and an adjustable standard or support for 35 sustaining the last mentioned frame, and means for operating said engine by steam or air obtained from the locomotive, substantially as 40 described.

7. The combination of a shaft or spindle 3 adapted to carry a tool within a locomotive cylinder, a frame adapted to be attached to said cylinder, an engine or motor carried by 45 said frame, a crank shaft carried by said frame and driven by said engine or motor, a pulley on said shaft, a frame 33 having one end journaled on said first mentioned shaft or spindle, a support for the opposite end of 50 said frame 33, and mechanism connecting said shaft 3 with the pulley on said crank shaft, substantially as described.

8. The combination of a shaft or spindle 3 adapted to carry a tool within a locomotive 55 cylinder, means for attaching said shaft to said cylinder, a frame having one end journaled on said shaft 3, a gear wheel arranged to turn said shaft 3 and to allow the latter to slide, a train of gearing for operating said 60 gear wheel, an engine for operating said train of gearing, and means for operating said engine by steam or air obtained from the locomotive, substantially as described.

9. The combination of a shaft 3 adapted to 65 carry a tool, means for attaching said shaft to a locomotive cylinder, a frame journaled on said shaft, gearing carried by said frame

for operating said shaft, a shaft 46 to operate said gearing, a pulley 47, belt 48, and a frame adapted to be attached to said cylinder, a 70 crank shaft carried by said frame, a pulley on said crank shaft to receive said belt 48, and an engine or motor carried by said frame for operating said crank shaft, substantially as described.

10. An adjustable frame consisting of a yoke 12 having a bar 12^a, a slotted bar 18 secured to said yoke, a slotted bar 20 having a bent end 20^b and bolt 19^a for adjustably holding said parts 18 and 20 together, and an extension 14 80 from said frame for attachment to a locomotive cylinder, substantially as described.

11. The combination of a mechanism adapted to be attached to a locomotive cylinder while in position on a locomotive for 85 boring or truing said cylinder, with means for facing or planing the valve seat, and means for operating said mechanisms conjointly and simultaneously, substantially as described.

12. The combination of a shaft or spindle 90 adapted to carry a tool or cutter, means for attaching said shaft to a locomotive or engine cylinder, an engine, and means for attaching it to a locomotive cylinder, and means for transmitting motion from said engine to said 95 shaft or spindle, with devices for facing or planing the valve seat of said cylinder, and means for transmitting motion from said engine to said planing devices, substantially as 100 described.

13. The combination of a plate, means for supporting it over a valve seat of a locomotive or engine cylinder, a rotative plate carried by said first mentioned plate, and a tool slide carried by said rotative plate, means 105 for intermittently moving said slide across said plate, with an engine or motor adapted to be attached to said cylinder, and devices connecting said engine or motor with said rotative plate, substantially as described.

14. The combination of a stationary plate, posts or supports for holding it above a valve seat of a cylinder, and supporting arms connecting said plate with said posts or supports having means for adjustment between said 115 parts, with a rotative plate carried by the first mentioned plate, a tool carrying slide mounted on the rotative plate, means for feeding said slide, a shaft carried by the first mentioned plate, and connections between 120 said shaft and the rotative plate, and an engine or motor adapted to be attached to said cylinder, and connections between said engine and said shaft, substantially as described.

15. The combination of a cutting mechanism arranged to face or plane a valve seat, means to fasten said mechanism upon a locomotive cylinder over a valve seat to face or plane said seat, said mechanism having an operating shaft, with an engine, means to attach it to said cylinder, the piston rod of said engine being connected with said operating shaft by a fly wheel, substantially as 125 described.

16. The combination of an adjustable frame adapted to be attached to a cylinder, a crank shaft journaled on said frame, a pulley 23 connected with said shaft and an engine 5 carried by said frame, with a boring shaft, means for supporting it centrally within said cylinder, a gear wheel carried by said shaft and arranged to turn the latter, a frame journaled at one end upon the hub of said wheel; 10 a train of gearing to turn said gear wheel, a shaft 46 carried by said frame, gearing connecting said shaft 46 with said train of gearing, a pulley 47 on the shaft 46 and a belt connecting the pulleys 23 and 47, substantially 15 as described.

17. The combination of a frame arranged to be attached to a cylinder, a crank shaft carried thereby, a pulley 23 connected with said shaft, and an engine carried by said frame to 20 operate said crank shaft, with a device for planing the valve seat of said cylinder, said device having a planing tool, a shaft and means for operating it to actuate said tool, a pulley on said shaft and a belt connecting 25 said pulleys, substantially as described.

18. The combination of a plate, means for holding it stationary, a shaft and means for turning it, sleeves 95, 96 mounted to slide on and turn with said shaft, and gears carried by 30 said sleeves, with a rotative plate supported by the stationary plate, the rotative plate having gears 87, a shaft 89 journaled on said stationary plate, a pinion 88 meshing with said gear 87, a gear wheel 90 carried by the shaft 35 89 and carrying a gear 99, a shaft 92 journaled on the stationary plate, a gear 91 on said shaft meshing with the gear 90, and a gear 100 on the shaft 92, and a tool slide carried by the rotative plate, and means for intermittently 40 feeding said slide, substantially as described.

19. The combination of a boring shaft or bar, means for supporting it within a locomotive cylinder, and means for moving said shaft longitudinally, with a wheel mounted on said 45 shaft, a spline and feather between said wheel and shaft, mechanism to turn said wheel, an engine for operating said mechanism, and means for attaching said engine to said cylinder, and means for operating said engine 50 by steam or air obtained from the locomotive, substantially as described.

20. The combination of a boring shaft or bar, and means for supporting it upon a locomotive cylinder, with a frame journaled at 55 one end upon said boring shaft or bar, gearing carried by said frame for turning said shaft or bar, and an adjustable standard connected with said frame, whereby it may be supported at its outer end relatively to the 60 shaft, substantially as described.

21. The combination of a boring shaft or bar, and means for attaching it to a locomotive cylinder, with a frame supported at one end upon said shaft or bar, mechanism carried by said frame for operating said shaft, and an adjustable standard 65 34 connected with said frame, said standard consisting of an

upright 34^b, and a yoke 34^a having cross bar 34^c and nuts 34^d to hold the part 34^b upon said cross bar, substantially as described. 70

22. The combination of a boring shaft or bar, means for supporting it within a locomotive cylinder, and a frame connected with said shaft and carrying mechanism for operating said shaft, and means for adjustably supporting the outer end of said frame, with an engine, a frame for supporting it, means for adjustably connecting said engine with said cylinder, and means for connecting said engine with the mechanism for operating said 75 boring shaft, whereby said frame may be adjusted to bring the parts into position for proper co-action, substantially as described.

23. The combination of an engine with a frame for supporting it, said frame having means for adjustably connecting it with a locomotive cylinder, and means for operating said engine by steam or air obtained from the locomotive, substantially as described. 80

24. The combination of an engine and frame 90 for supporting it, said frame having means for adjustably connecting it with a locomotive cylinder, with a boring shaft or bar, means for connecting it with said cylinder, a frame having mechanism for operating said 95 shaft, and means for adjusting said frame relatively to said engine-supporting-frame, whereby the parts may be brought into alignment for proper co-action, substantially as described. 100

25. The combination, of an engine, an adjustable frame for supporting it, and a plate having a curved slot for adjustably connecting it with a locomotive cylinder, and means for operating said engine by steam or air obtained from the locomotive, substantially as 105 described.

26. An engine having a supporting plate 14 provided with a curved slot for adjustably connecting it with a locomotive cylinder, and means for operating said engine by steam or air obtained from the locomotive. 110

27. The combination of an engine, with a frame for supporting it, said frame carrying a plate having a portion that is adjustable to 115 enable the frame to be attached to a locomotive cylinder, and means for operating said engine by steam or air obtained from the locomotive, substantially as described.

28. The combination of an engine, with a frame having an extensible portion arranged to be secured to a locomotive cylinder, and a yoke-like portion supporting said engine, said yoke-like portion being adjustably connected with the extensible portion of the frame, and 125 means for adjustably connecting the yoke-like portion of the frame to a locomotive cylinder, whereby the frame may be adjusted on said cylinder to bring the engine into proper operative position, substantially as described. 130

29. The combination of an engine, with a frame, means for adjustably connecting it with a locomotive cylinder, said frame having a yoke-like portion, said yoke carrying

bearings, a crank journaled in said bearings, the piston of said engine being connected with said crank, and means for operating said engine by steam or air obtained from the locomotive, substantially as described.

30. The combination of a frame arranged to be connected with a locomotive cylinder, said frame having a plate 13, with an oscillating engine pivotally carried by said plate, and means for supplying said engine with steam or air obtained from said locomotive, substantially as described.

31. The combination of a frame arranged for attachment to a locomotive cylinder, an engine carried by said frame, a shaft jour-

naled on said frame and connected with the piston of said engine, pulleys 23 and 24 carried by said shaft, a boring shaft or bar, means for supporting it in said cylinder, mechanism for operating said shaft or bar, connections for operating said mechanism by the pulley 23, mechanism for facing or planing the valve-seat of the cylinder, and connections from said mechanism to the pulley 24, substantially as described.
